FEEDBACK ANTENNA SYSTEM

George T. Royden, South Orange, N. J., assignor
to Federal Telephone and Radio Corporation,
New York, N. Y., a corporation of Delaware

Application April 9, 1945, Serial No. 587,239

15 Claims. (Cl. 250—17)

1

This invention relates to a directive antenna and generating system, especially to a low frequency directive antenna system and an efficient means for generating the power for exciting the antenna.

This invention permits the use of the same frequencies at several stations without excessive interference and thus allows the use of a number of radio communication channels.

This invention makes use of an inverted amplifier, long line frequency stabilization and a wave antenna terminated in its surge impedance, each known per se, in a novel combination and in conjunction with other features hereinafter specified.

The invention is diagrammatically illustrated in the accompanying drawings, wherein:

Fig. 1 shows an antenna circuit fed by the plate tank circuit of an inverted triode and inductively coupled to its cathode circuit;

Fig. 2 shows a modification thereof including an artificial line;

Fig. 3 is another modification of Fig. 1, wherein the cathode circuit is frequency modulated; and

Fig. 4 shows the schematic arrangement of a directive antenna and generating system including two antennae.

The basic elements of a system embodying the invention are shown in Fig. 1 in which a vacuum tube 1 has its cathode heated by battery 2 and receives plate current from battery 3. Inductance coil 4 and capacitor 5 are tuned to the desired operating frequency. Power from the vacuum tube passes through the plate tank circuit to inductor 6 which is connected between ground and the sending end of the antenna, connection being made to the center tap of inductor 7; one end of inductor 7 is connected to antenna wire 8 and the other end to antenna wire 9. Capacitor 26 serves to neutralize the reactance of inductor 6 and the leakage reactance of the two halves of inductor 7. Because of symmetry, half of the total antenna current flows in each of the wires 8, 9 and the current in one wire is in phase with the current in the other wire.

Antenna wires 8 and 9 should be elevated above ground so as to be efficient radiators for the power fed to them via inductor 7. As the radiated wave travels in the direction of long arrow A parallel to the antenna wires 8, 9, power is continuously added to the wave by radiation from that portion of the antenna adjacent to the wave. In this manner the amplitude of the wave increases as it approaches the end of the antenna at inductor 10.

2

Because of radiation of energy and the losses in the antenna and the ground below the antenna, the current in the antenna will be attenuated as it flows along the antenna towards inductor 10.

The currents arriving in each antenna wire 8, 9 at inductor 10 enter this inductor at its ends and flow to the center tap where they combine. The combined current then passes through capacitor 27 and inductor 11 which is coupled to inductor 10, to ground at 12. The amount of coupling is so chosen that the terminating impedance of the antenna when reflected through the coupled circuits will be equal to the surge impedance of the transmission line formed by wires 8 and 9. Capacitor 27 serves to neutralize the reactance of inductor 11 and the leakage reactance of the two halves of inductor 10. In this manner the antenna will be so terminated that except for coil losses all of the energy arriving at the end will be transmitted into the transmission line and none will be reflected at the end of the antenna; standing waves will not be present. Consequently there will be negligible radiation in the reverse or undesired direction.

The current flowing through inductor 11 induces a voltage in inductor 10 as a result of which current flows in the transmission line as shown by the short arrow B. This return current will flow back through the transmission line formed by the antenna wires 8 and 9 to inductor 7.

The distance between wires 8 and 9 is small in comparison with the height of the wires above ground so that they will act as an efficient transmission line for the return current. Radiation from this return current will be negligible.

The return current flowing through inductor 7 will induce a voltage in inductor 13 coupled thereto. The resulting current through inductor 13 builds up a voltage between the cathode of vacuum tube 1 and ground 15. In the circuit of Fig. 1, capacitor 25 should be so adjusted that the circuit containing capacitor 25 and inductor 13 is at resonance for the desired operating frequency.

Since the grid is grounded, the voltage across capacitor 25 also constitutes the excitation voltage between grid and cathode of vacuum tube 1. This voltage appearing from cathode to ground across capacitor 25 is in phase with the voltage existing across the load circuit of vacuum tube 1 with respect to ground because the vacuum tube acts as an amplifier. Thus, part of the power received over the transmission line will be used for

excitation of vacuum tube 1 and the remainder will be returned to the load circuit.

In this manner the power which would ordinarily be dissipated in the impedance matching resistor at the terminal of the directive antenna is utilized. A further advantage of this system is that, because of the power returned to the circuit, the power is higher than would otherwise be produced in the vacuum tube 1.

The frequency of operation is determined partly by the resonant circuits constituted by inductor 4 and capacitor 5 also inductor 13 and capacitor 25, but principally by the total length of the transmission path extending through the antenna to the far end and back through the transmission line to the input circuit of vacuum tube 1. The precise frequency will be such that the voltage arriving at the grid with respect to the cathode will be 180 electrical degrees out of phase with the voltage in the anode circuit of vacuum tube 1 with respect to ground.

In Fig. 2 in addition to the elements previously described, an artificial line is shown comprising capacitors 16 and 17 and inductor 18. One or more of the elements of this artificial line may be made variable. They serve to change the equivalent electrical length of this line and to adjust the operating frequency.

Fig. 2 also provides a grid capacitor 19 and a grid leak resistor 20. The cathode circuit contains inductors 21 and 22, by-passed by capacitors 23 and 24. Capacitor 25 serves to resonate inductors 21 and 22. Capacitor 28 neutralizes the reactance of inductor 13.

A series of capacitors 29, 30, 31, 32, 33, 34 . . . 39 and 40 is arranged in series with portions of the antenna. Capacitors 26, 27, 29, 30, 39 and 40, neutralize, in part, the reactances of inductors 7 and 10. Capacitors 31, 32, 33 and 34 provide a means for changing the characteristics of the antenna so that the apparent velocity of propagation of the current flowing towards inductor 10 can be made equal to the velocity of propagation of the radiated wave. This improves the transfer of power from the antenna to the radiated wave.

Fig. 3 shows a system for frequency modulation. Inductor coil 18 in the artificial line is coupled to another inductor coil 41. This latter coil is in the plate circuit of a modulator vacuum tube 42 the grid circuit of which is controlled by the signal intelligence to be transmitted. Variations in the voltage impressed on the grid circuit of vacuum tube 42 cause a change in impedance shunted across inductor 41. This change is reflected by a change in reactance of coil 18 and consequently a variation in the frequency of oscillation.

Two or more antennae similar to those described may be employed for the purpose of obtaining a better directional radiation pattern. This is schematically explained in Fig. 4. Local auxiliary antenna 43 is so located that its maximum radiation is in the direction of local receiving station (not shown) intended for reception of signals on the same frequency from another local source 44. Phase and magnitude of the current supplied to antenna 43 from source 46 should be so adjusted that the radiation from this antenna counter-balances the radiation from the main antenna 45 in the direction of the receiving station.

Alternatively, the two antennae 43, 45 can be supplied, instead of from two separate sources 44, 46, from a common single source 47 with a

phase shifting or phase balancing device 48 arranged between source 47 and antenna 43 as indicated in Fig. 4, in dotted lines.

Other variations may be made by one skilled in the art without exceeding the scope of this invention.

What I claim is:

1. In combination, an antenna system, an amplifier including a cathode circuit and a plate tank circuit, said antenna system substantially radiant acting to energy received from said plate tank circuit, said cathode circuit coupled to receive the energy not radiated by said radiant acting antenna system and returned back over said radiant acting antenna system to provide said amplifier with regenerative energy.

2. A system according to claim 1, wherein said amplifier has a grounded grid.

3. A system according to claim 1, wherein said antenna system comprises a closed transmission line including an input impedance connected to the plate tank circuit and a terminating impedance coupled to ground, the amount of coupling being such that the terminating impedance when reflected through the coupled circuits will be substantially equal to the surge impedance of the transmission line.

4. In a system according to claim 1, an antenna system comprising at least a pair of antenna wires elevated above ground, a first inductance having ends connected to one end of said antenna wires and having a center connection to the plate tank circuit, a second inductance connected to the other end of said antenna wires and inductively coupled to ground, the amount of coupling being such that the terminating impedance when reflected through the coupled circuit will be equal to the surge impedance of the transmission line formed by said antenna wires.

5. In a system according to claim 1, an antenna system comprising at least a pair of antenna wires elevated above ground, a first inductance having ends connected to one end of said antenna wires and having a center connection to the plate tank circuit, said center connection forming two halves of said first inductance, a second inductance connected to the other end of said antenna wires and inductively coupled to ground, the amount of inductive coupling of said second inductance being such that the terminating impedance when reflected through the coupled circuit will be equal to the surge impedance of the transmission line formed by said antenna wires, said inductive coupling including a third inductance connected to ground, and means including a capacitance for neutralizing the reactance of said third inductance and of the leakage reactance of the two halves of said first inductance.

6. In a system according to claim 1, a cathode circuit tuned at resonance with the operating frequency of said antenna system.

7. In a system according to claim 1, an amplifier consisting of a vacuum tube triode, means for operating said triode inversely, said means including a control grid for said triode connected to ground, input and anode circuits for said triode, resonant circuits included in said input and anode circuits and determining the frequency of operation together with the total length of the transmission path extending through said antenna system to the far end and back to the input circuit, the voltage arriving at the control grid being 180 electric degrees out of phase with the voltage in the anode circuit.

8. In a system according to claim 1, an antenna

system forming an artificial line and variable elements for changing the equivalent electrical length of said artificial line to adjust the operating frequency.

9. In a system according to claim 1, a cathode circuit including inductors by-passed by capacitors for resonating said inductors and neutralizing the reactance of the coupling.

10. A system according to claim 1, an antenna system comprising a closed transmission line including an input impedance connected to the plate tank circuit and a terminating impedance coupled to ground, the amount of coupling being such that the terminating impedance when reflected through the coupled circuits will be substantially equal to the surge impedance of the transmission line, said transmission line comprising means for changing the characteristics of said antenna system so that the apparent velocity of propagation of the current flowing towards said input inductance is made substantially equal to the velocity of propagation of the radiated wave.

11. In a system according to claim 1, a cathode circuit inductively coupled to said antenna system and forming therewith an artificial line.

12. In a system according to claim 1, a cathode circuit inductively coupled to said antenna system and forming therewith an artificial line, and modulating means coupled to said artificial line.

13. In a system according to claim 1, a cathode circuit inductively coupled to said antenna system and forming therewith an artificial line, a first inductance in said artificial line, a second inductance coupled to said first inductance, a modulator tube having a plate circuit coupled to said second inductance and having a grid circuit controlled by signal intelligence to be transmitted so as to cause a change in impedance shunted

across said second inductor said change being accompanied by a change in reactance of said first inductance and a modulation in the frequency of oscillation.

5 14. In an antenna system of the type in which the antenna serves as a frequency determining transmission line element in the feedback circuit of an oscillator; the combination of means coupling said oscillator to said antenna to provide a radiating wave traveling over said antenna and terminating coupling means for said antenna for feeding back the unradiated portion of said wave over said antenna to said oscillator.

10 15. An antenna system comprising an amplifier, a two conductor antenna, means for coupling the output of said amplifier to said antenna in such energy transfer relation that current flow is in the same direction in said conductors, and terminating means for returning energy to the input of said amplifier in such relation that current flow is in opposite directions in said conductors.
